[57] CLAIM

The ornamental design for a tree cutter attachment for a tractor or like apparatus, as shown and described.

DESCRIPTION

FIG. 1 is a top plan view of the claimed tree cutter attachment for a tractor or like apparatus showing my new design;

FIG. 2 is a view in side elevation of the claimed design, where the opposite side is a mirror image thereof;

FIG. 3 is a view in elevation, looking from left to right in FIG. 2, showing certain details of the claimed design; and,

FIG. 4 is another view in elevation, in this instance looking from right to left in FIG. 2, showing further details of the claimed design.
